FRANCIS J. JOHNS, OF WILKINSBURG, PENNSYLVANIA, ASSIGNOR TO WESTINGHOUSE ELECTRIC & MANUFACTURING COMPANY, A CORPORATION OF PENNSYLVANIA

SQUIRREL-CAGE PUMP MOTOR OR THE LIKE

Application filed October 22, 1929. Serial No. 401,574.

My invention relates to a rotor slot arrangement for reducing the starting currents in a motor in which it is desired to have not only a reasonably good starting torque but also a good performance under running conditions; and it has more particular reference to such motors for driving centrifugal pumps, which do not require exceptionally high starting torques because a centrifugal pump does not take its load until it has come up to speed.

My invention has particular relation to deep-bar squirrel-cage motors in which the eddy currents in the squirrel-cage bars affect the starting conditions by crowding the secondary currents to the tops of the bars at starting, thereby increasing the resistance of the squirrel-cage at starting. The effect of the eddy currents in the deep bars is not only to increase the starting resistance, which is desired, but to decrease the inductance, because the bar acts, on starting, as if it were shallower than it really is. The decrease in inductance at starting is detrimental to the securing of a low value of starting current, since the reactance of the motor is the greater part of its impedance on starting. The increase in bar resistance is advantageous since it increases the starting torque.

The standard construction of deep-bar motors accomplishes the right resistance conditions at starting, but the inductance change is just opposite to the ideal conditions, which would be a motor having a higher inductance at starting than under running conditions.

According to my present invention, I have approached the ideal condition of a deep-bar squirrel-cage motor by keeping the inductance at start approximately the same as the inductance under load, the inductance being only slightly higher under load conditions than at start.

My invention will be explained after a description is given of a preferred embodiment thereof, with reference to the accompanying drawing, wherein

Figure 1 is a fragmentary transverse sectional full-scale drawing of the rotor member of a three-phase, 50-horsepower, 4-pole,

60-cycle, 1750 R. P. M. motor embodying my invention,

Fig. 2 is a curve chart hereinafter explained, and

Fig. 3 is an enlarged view showing one of the rotor slots, with the conductor therein shown in section.

As shown in Fig. 1, the steel rotor punchings 3 of my motor are provided with a plurality of deep perforations or so-called "slots" 4 in which are disposed the squirrel-cage bars 5 which are preferably made of hard-drawn copper and rectangular in cross-section. The bars 5 are buried in the rotor to provide a bridge 6 over each of the slots or perforations 4, and each bridge is slotted, in a radial direction, by a slit 7 which is as narrow as it is economically practical to make it, with a reasonable life of the punching dies, and which extends upwardly from the top of the slot 4 to within a few hundredths of an inch of the outer periphery of the rotor punching 3. At present, I am making the slits 31 mils wide, but I contemplate making the slits of even narrower widths.

The ratio of the bar-resistance at starting and at full speed, respectively, is dependent upon the slot or bar-depth d , regardless of the bar-width b , and it is also proportional to the square root of the frequency $\sim$ (usually expressed in cycles per second) and inversely proportional to the square root of the resistivity ρ (which may be conveniently expressed in ohms per inch cube). The manner in which the ratio of the bar-resistance at starting to the bar-resistance at full

speed varies for different values of $X = d \sqrt{\frac{\sim}{\rho}}$ is shown in the upper portion of Fig. 2, where the number of superposed conductors per slot is indicated by m . In general, my invention would be applied only to a rotor having a single conductor per slot, following the curve $m=1$, although, in exceptional cases, the other curves might be followed.

The ratio of the slot-inductances at starting and at full speed are also dependent upon $X = d \sqrt{\frac{\sim}{\rho}}$, the manner of variation being

indicated by the curves in the lower portion of Fig. 2.

From the curves in Fig. 2, it will be seen that, for a rotor bar having three times as much resistance at starting as at running speed, the starting inductance of the portion of the slot in which the bar is located will be only one-half as much as the running inductance thereof. As pointed out above, this is more of a decrease in the inductance, at starting than is desirable, because of its effect in increasing the starting current without a proportional increase in the starting torque.

Heretofore, it has been customary, where a larger starting reactance is required in a motor of the character under consideration, to add a few more turns of primary winding, which has the effect of decreasing the flux density and increasing both the primary and the secondary leakage reactances of the motor in proportion to the square of the primary turns, so that the total reactance of the motor is increased at starting, as desired. The objection to this practice is that it increases the primary resistance, thereby reducing the full-load speed and the efficiency and, sometimes, the power factor of the motor under running conditions.

According to my invention, I overcome the detrimental effect of this 50% reduction in the slot-inductance of the bar, at starting, by the use of a slotted bridge 6 which has the following properties. If the slit-width is w and the slit-depth t , the slot-factor for the slotted portion of the bridge, (which determines the slot-reactance of this portion of the slot at full load) is $\frac{t}{w}$. The slot factor, which defines the full-load leakage reactance across the portion of the slot occupied by the conductor bar 5, is $\frac{d}{3b}$. The total slot-reactance at full load is thus proportional to $\frac{t}{w} + \frac{d}{3b}$.

being determined solely by the shape of the slot, and regardless of the material of the conductor bar 5. It will be noted, however, that the inductance indicated by the first factor does not vary at starting, whereas that indicated by the second factor is reduced by, say, 50% at starting.

According to my invention, I make the first factor

$$\frac{t}{w}$$

so large, as compared with the second factor

$$\frac{d}{3b}$$

that the reduction in the inductance of the second factor at starting shall be a small portion of the total inductance, thereby approaching the condition of a motor having a starting secondary inductance approximately

as high as the secondary running inductance.

It will be noted from the drawing and from the previous description of the slit 7 in the bridge 6 over each slot that there is a small iron bridge-portion 8 over each of the slits 7. In order to explain this, it is necessary to refer to the manner in which the rotor punchings 3 are prepared and assembled.

The accurate assembly of the rotor punchings is not as easy as the accurate assembly of the stator punchings which are built on an expanding arbor and are thus very accurately assembled without much trouble or expense. The rotor punchings are assembled, however, on a shaft of relatively small diameter, and it is not economical to go to such extreme refinements of assembly as will ensure a reasonably smooth outer periphery of the finished rotor, so that it is customary to turn down the periphery after the rotor is finished and mounted on its shaft. It is frequently desirable, as in the motor which is shown in Fig. 1, to utilize, for the rotor punchings, the discs which are punched out of the inner peripheries of the stator punchings, so that the turning down of the finished rotor has also the function of determining the depth of the air-gap, which may be something like twenty-one thousandths of an inch on each side of the rotor.

It is not practicable to turn down a rotor in which the slits 7 extend all the way through to the outer periphery of the rotor, as the tool catches on the slits and causes very considerable trouble. According to my design, the distance above the slit may be something of the order of a few hundredths of an inch, so that, after the rotor is turned down, as indicated by the broken line in Fig. 1, the depth of metal between the top of the slit and the outer periphery shall be about ten thousandths of an inch.

It is desirable that this metal shall be as thin as possible because it conducts leakage flux; and, under the heavy starting-current conditions, it becomes saturated and thereby introduces a small but appreciable harmful effect, adding about 0.5 to the slot factor. If this metal bridge is made to have a depth less than ten thousandths of an inch, the cutting tool dips down and catches in it during the turning operation, as described above. It is believed that this innovation of a 10-mil iron bridge over a slotted bridge of a machined rotor-member is an important feature of my contribution to the art.

It will be noted that the bar-width b has no effect upon the manner in which the reactance and the resistance vary from starting to full speed but that it has a direct effect upon the portion of the slot-inductance resulting from the transverse flux crossing the bar. As this is the variable portion of the slot-inductance, it is desirable to make it as small as possible, or, in other words, to make the slot-width b

as large as possible. The slot-width is rather closely determined, however, by the total amount of copper which is needed in the rotor, in order to obtain the torque, speed and power required of the motor, and the design is also limited by the necessity for preventing excessive flux-densities in the iron teeth between the deep, narrow slots 4 in which the bars are located. The total depth of slot, that is, the distance of the bottom of the bar 5 from the outer periphery of the rotor, is also strictly limited by the necessity for avoiding saturation of the iron underneath the slot, as well as in the teeth between the slots.

It is an important feature of my invention, therefore, to make the slits 7 as narrow as possible, because the effect of the slotted bridge 6 is inversely proportional to the thickness of the slits, or, in other words, the depth t of the bridge, for a given constant reactance effect, is inversely proportional to the slit-width w , so that, if the slit is of any considerable width, the effect of any practicable bridge-depth which could be utilized, in a commercial deep-bar-rotor slot, would be quite small and unimportant.

While my invention is not altogether limited to the material of the rotor bars, I have so far found that the practical commercial designs require the use of copper bars, which are most readily obtained as hard-drawn copper bars of rectangular-cross-section. Cast aluminum, which usually has a resistivity of approximately twice that of copper, and brass, having a resistivity of approximately four times that of copper, would both require a greater slot depth and a greater space in which to put the rotor bars than are available in any commercial design for the class of service for which my motor is primarily intended, as outlined hereinabove.

I prefer to employ bars 5 and slots 4 of substantially rectangular shape as being the most practicable, for the following reasons. If the sides of the bars and of the slots 4 are made radial, the bars would be of wedge-shape, with a slightly greater thickness at the top than at the bottom, but they would still be substantially rectangular, since the depth of the bar is something of the order of one-quarter of the radius of the rotor, so that the thickness of the lower edge of the bar could not be less than about $\frac{3}{4}$ of thickness of the outer edge of the bar. While a bar of the form just mentioned would have more conductor material than the bar shown in Fig. 1 of the drawing, a conductor having a wider top than bottom would have less change in its resistance, as well as in its inductance, on starting, than a strictly rectangular bar, so that a deeper bar depth would be required in order to bring the resistance-ratio up to the value obtainable with a rec-

tangular bar, if the conductor were materially wider at the top than at the bottom. With a bottom which is three-fourths as wide as the top of the bar, the formula

$$\frac{d}{3b} \quad 70$$

for the slot-factor of the bar is accurate within 10%, if the breadth b is taken as the thickness of the top of the bar. 75

If the slot should be made narrower at the top than at the bottom, both the resistance and the inductance would be changed more, on starting, than in a rectangular bar and slot. However, this would mean a serious reduction in the width of the teeth at the inner peripheries of the slots, and, as this minimum thickness of tooth cannot be reduced, it would mean either a larger and more expensive motor or less material in the rotor conductors, and, hence, too great a resistance during running conditions, which would mean poor performance, that is, a low speed and a poor efficiency, with almost certain overheating in the rotor. Here again, it is obvious that no material departure from a rectangular bar cross-section is possible, and, if the thickness of the bar at the top is $\frac{3}{4}$ of the thickness of the bar at the bottom, the formula

$$\frac{d}{3b} \quad 95$$

is again accurate within 10%, if the thickness b is measured at the top of the bar, as before. 100

Cylindrical conductors and slots are out of the question in a squirrel-cage motor in which any material eddy-current effect is desired. The slot factor is .625, regardless of its diameter, but the material of the conductor bar is so placed as to require a very great thickness b and depth d , resulting in extreme saturation of the teeth and of the iron core below the conductors. In short, it is not commercially practicable to make an induction motor utilizing the eddy-current effect to secure a good starting torque, with a cylindrical slot construction. 105

Certain practical limits may be noted. Thus, with hard-drawn copper bars operating at 75° C. at full load, the resistivity of the bar material is about $.84 \times 10^{-6}$ ohms per inch cube. In a sixty-cycle, copper-bar motor, the abscissas X in Fig. 2 would have to be multiplied by .00012, in order to obtain the bar depth d in inches. Thus, a bar having a starting resistance three times its running resistance would have approximately a bar depth of $9100 \times .00012 = 1.1$ inches. 110 It is believed that this calculation will be sufficient to illustrate the use of the curves in Fig. 2. 120

In general, it may be said that the ratio of secondary or squirrel-cage resistances, at 130

starting, as compared with running, of a satisfactory motor of the type to which my invention is at present applied should be approximately 3 or more, or, at least, greater than 1.8 or 2. The reactance in the bridge portion of the slot should be at least approximately as large as the slot-reactance below the bridge at running speeds, or it should be such as to bring the ratio of the total slot-inductance, as starting, as compared with the total slot-inductance at full-load running speed, to a value at least as high as about $\frac{2}{3}$, and preferably around 72% or 80%.

For a copper bar, the depth should preferably be at least an inch, in a 60-cycle motor, and, in general, it is desired that the ratio of d to

$$\sqrt{\rho}$$

shall be at least about 1200; and that

$$d \sqrt{\frac{\rho}{\rho}} > 9,000,$$

or, in extreme cases, it may be as low as 6,000.

For a copper-bar motor operating at a frequency other than 60 cycles, it may be said that

$$d \sqrt{\frac{\rho}{\rho}} > 7.$$

The capacity-range of the motors of which I am primarily considering, in describing my invention, is from 40 horsepower to 100 horsepower, in 4-pole and 6-pole designs, or, in general, the range of sizes is something of the order of 5 to 300 horsepower capacity. The bar-depth will remain fairly constant, at preferably $1\frac{1}{4}$ to $1\frac{1}{2}$ inches, regardless of the horsepower although, possibly, in motors of the larger sizes, it may sometimes be practicable to utilize a somewhat greater bar-depth. Expressed in formula form, I should say that the bar-depth should be at least such that

$$d \sim^{1/2} > 6P^{1/20},$$

where P is the capacity in horsepower.

As to the physical dimensions of the slit in the bridge, I should say that the slit-depth t should be so great, and the slit-width w so small, that tb is at least as large as about one-third of dw . I prefer that the ratio

$$\frac{t}{w},$$

representing the slot-factor of the slotted portion of the bridge, shall be well over 4, although, in extreme cases, I believe that less desirable but still useful results would be obtained with a slot-factor as low as 2, or

$$2P^{1/20}.$$

In the foregoing specification, I have attempted to indicate the fundamental principles of my invention and to delimit the quantitative values of the novel features of my motor design.

I realize, of course, that certain changes and departures from my preferred designs may be made without departure from the essential spirit and results of my invention, and I have attempted to explain the scope and nature of some of the said changes. I do not desire to be limited to my exact design except as specified in the appended claims when read in the light of the prior art.

I claim as my invention:

1. A sixty-cycle squirrel-cage induction motor having substantially rectangular deep bars of such depth d (in inches), as compared with their resistivity ρ (in ohms per inch cube), that the ratio of d to

$$\sqrt{\rho}$$

is at least about 1200, characterized by having slotted bridges above the squirrel-cage bars, and characterized further by having such bar-width b , slit width w and slit depth t that tb is at least as large as about one third of dw .

2. A squirrel-cage induction motor having substantially rectangular deep bars of such depth d (in inches), as compared with their resistivity ρ (in ohms per inch cube) and the line frequency $\sim$ (in cycles per second), that

$$d \sqrt{\frac{\rho}{\rho}} > 9,000$$

characterized by having slotted bridges above the squirrel-cage bars, and characterized further by having such bar width b , slit width w and slit depth t that tb is at least as large as about one third of dw .

3. A squirrel-cage induction motor having substantially rectangular deep bars of such depth d (in inches), as compared with their resistivity ρ (in ohms per inch cube) and the line frequency $\sim$ (in cycles per second), that

$$d \sqrt{\frac{\rho}{\rho}} > 6,000,$$

characterized by having slotted bridges above the squirrel-cage bars, and characterized further by having such bar width b , slit width w and slit depth t that tb is at least as large as about one third of dw .

4. An iron-core, copper-bar, sixty-cycle squirrel-cage induction motor having substantially rectangular bars at least 1 inch deep, characterized by having slotted bridges above the squirrel-cage bars, the slit having such width w and depth t that the ratio

$$\frac{t}{w}$$

is greater than 4.

5. An iron-core, copper-bar, sixty-cycle squirrel-cage induction motor having substantially rectangular bars at least 1 inch deep, characterized by having slotted bridges above the squirrel-cage bars, the slit having

125

130

such width w and depth t that the ratio

$$\frac{t}{w}$$

5 is greater than 2.

6. An iron-core, copper-bar, squirrel-cage induction motor characterized by having such bar-depth d (in inches), as compared with the line frequency $\sim$ (in cycles per second) and 10 capacity P (in horsepower), that

$$d \sim^{1/2} > 6P^{1/20},$$

and characterized further by having slotted bridges above the squirrel-cage bars, the slit 15 having such width w and depth t that the ratio $\frac{t}{w}$ is greater than $3P^{1/20}$.

7. The invention, as defined in claim 3, 20 characterized by the fact that the slits in the bridges are closed at the air-gap periphery by an iron core-portion having a depth of the order of 10 mils.

8. The invention, as defined in claim 4, 25 characterized by the fact that the slits in the bridges are closed at the air-gap periphery by an iron core-portion having a depth of the order of 10 mils.

9. The invention, as defined in claim 6, 30 characterized by the fact that the slits in the bridges are closed at the air-gap periphery by an iron core-portion having a depth of the order of 10 mils.

In testimony whereof, I have hereunto 35 subscribed my name this 18th day of October, 1929.

FRANCIS J. JOHNS.
